DRILL SHARPENING MECHANISM

Filed Jan. 5, 1923

by Frank M. Lee. Inventor:
Base Color Office Conn.

UNITED STATES PATENT OFFICE.

FRANK M. LEE, OF CHICAGO, ILLINOIS, ASSIGNOR TO SULLIVAN MACHINERY COMPANY, A CORPORATION OF MASSACHUSETTS.

DRILL-SHARPENING MECHANISM.

Application filed January 5, 1923. Serial No. 610,928.

My invention relates to drill sharpening mechanisms, and more particularly to hole opening punches of a variety employed in reopening the cleansing fluid conducting passages through hollow drill steels when the latter have been closed or obstructed by certain of the operations to which the steels are subjected in formation or resharpening.

10 An object of my invention is to provide an improved hole opening mechanism of the type described. Another object of my invention is to provide an improved hole opening mechanism having improved controlling means. A further object of my invention is to provide an improved percussive tool operated hole opening punch having means for automatically controlling the operation of the percussive tool in accordance with the position of the work with relation to the punch. Other objects and advantages of my invention will hereinafter more fully appear.

25 In the accompanying drawings I have shown for purposes of illustration one form which my invention may assume in practice.

In these drawings,

30 Fig. 1 is a view partially in elevation and partially in central longitudinal vertical section through one illustrative form of my improved mechanism.

35 Fig. 2 is a view partially in elevation and partially in vertical transverse section on the line 2—2 of Fig. 1.

Fig. 3 is a detail sectional view showing a portion of the controlling mechanism.

In this illustrative form of my invention, the same is shown mounted upon a supporting frame 1, which frame carries at its rear end, that is, the end away from which the blacksmith stands during the drill sharpening operation, a percussive punch operating or pinning motor 2 which is shown more or less diagrammatically, as it may assume any desired form, and to which motive fluid is supplied through a passage 3, the motive fluid being distributed herein by a piston 4 which reciprocates in the cylinder 5 of the motor 2 and conducted after distribution by the piston by bypass passages 6 and 7 to the ends of the cylinder, and being exhausted at appropriate times through exhaust ports 8 and 9.

55 Supported in the front end of the motor

2 is a hole opening punch member 10 which is retained within the reach of the percussive piston 4 by spring tool retaining means 11, it being noted that the punch member has a limited freedom of movement before it strikes the spring retaining means so that during hole opening the entire force of the blow is expended on the work. Arranged adjacent the opposite end of the frame member 1 is a vise mechanism generally indicated by 13 which comprises a pair of cooperating jaws 14 and 15 respectively provided with steel clamping notches 16 and 17 of such shape as automatically to center any steel with which they may be used. The jaws 14 and 15 are further respectively provided with depending lugs 18 and 19 which are internally threaded as at 20 and 21 and constitute nuts having oppositely arranged threads and cooperating with a longitudinally fixed but rotatable screw member 23 journaled in and held against longitudinal movement by a bearing 24 in a carriage member 25. The member 23 may be rotated by a handle 26 and will, depending upon the direction of rotation, cause the vise jaws to approach each other or to separate. It will be understood that the vise jaws are suitably guided, in an appropriate manner, for sliding movement transversely in the carriage 25. The carriage 25 is longitudinally movable in the guides 28 carried by the top of the frame 1. A rack 29 is carried by the carriage 25 and an arcuate toothed member 30 interengages with the rack and, being pivoted upon a shaft 31 which may be rocked in bearings 32 upon the frame 1, is capable of effecting longitudinal movement in opposite directions of the carriage 25. For the purpose of oscillating the shaft 31, a lever 33 is secured thereto, which lever is provided with a manually releasable latch member 34 cooperating with a fixed abutment 35 upon the frame member 1. It will be observed that when the carriage is in its rearmost position, the lever 33 is held by the latch 34 and abutment 35 and accordingly that the carriage 25 cannot move forwardly except at the will of the operator. A fluid supply connection 37 controlled by a valve 38 communicates by a passage 39 with the passage 3 previously referred to. The valve 38 has a stem 40 projecting through the cover of its housing 41 and adapted to be engaged by spring 110

pressed abutment member 42 carried in the rear end of the frame member 25, the member 42 being backed by a spring 43 of such strength as to be able to overcome the pressure of the motive fluid upon the valve when the latter is closed, and to maintain the valve closed until the carriage starts upon its movement toward the motor 2.

The mode of operation of my improved mechanism will be clearly apparent. By operation of the handle 26 the vise jaws 14 and 15 are moved to receive and clamp a drill steel D. The handle 33 is then moved in a clockwise direction (Fig. 1) after the latch 5 has been released. As a result of the movement of the handle 33, the toothed member 30 cooperates with the rack 29 to move the frame 25 and with it the drill steel D toward the pinning tool 10. The carriage 25 is moved by operation of the lever 33 in such manner as to cause the pin to penetrate for the necessary distance into the hole in the steel D and when the hole has been opened to the necessary amount, the movement of the handle 33 is reversed and the steel drawn back. In case the pin sticks it will be more readily loosened by reason of the hammering during retraction. It will also be observed that as soon as the carriage 25 starts to move toward the pinning tool, the valve 38 is opened by the pressure of the fluid transmitted through the pipe 37 and fluid then passes by way of passage 39 and passage 3 to the motor 2 and causes the piston to reciprocate and actuate the tool 10. It will further be noted that the motor is operated during the entire forward movement of the drill steel D and will continue to operate until the steel has been moved entirely out of the range of action of the tool 10 and the carriage returned to its rearmost position in which it will be held by the latch 34. The drill steel D may then be removed and other steels operated on in a similar manner.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. In a hole opening mechanism, a stationary motor operated pinning device, a drill steel clamping device, manual means for moving said clamping device longitudinally relative to said pinning device, means associated with said manual means for normally holding said clamping device in a position remote from said pinning device, and means controlled by movement of said clamping device for controlling the supply of operating fluid to said motor operated pinning device.

2. In a hole opening punch, a stationary percussive motor adapted to operate on a hollow drill steel, means for feeding said steel toward and away from said motor, and means including a resilient abutment carried by said feeding means for starting and stopping said motor.

3. In a hole opening mechanism, a stationary motor operated pinning device, a drill steel clamping device, actuating means for moving said clamping device longitudinally relative to said pinning device, means associated with said actuating means for normally holding said clamping device in a position remote from said pinning device, and means automatically controlled on movement of said clamping device for controlling the supply of operating fluid to said motor operated pinning device upon approach thereto of said clamping device.

In testimony whereof I affix my signature.

FRANK M. LEE.
